The ornamental design for a hybrid integrated circuit for electric power control, as shown and described.

DESCRIPTION

FIG. 1 is a perspective view of the front, bottom and right side of a hybrid integrated circuit for electric power control showing our new design;

FIG. 2 is a top plan view thereof;

FIG. 3 is a front elevational view thereof;

FIG. 4 is a bottom plan view thereof;

FIG. 5 is a rear elevational view thereof; and,

FIG. 6 is a left side elevational view thereof, the right side being a mirror image thereof.
